FEEDING OF BISCUITS OR OTHER SWEET-MEATS TO CHOCOLATE ENROBING MACHINES AND THE LIKE

Allan Ashmead Tunley, Peterborough, England,
assignor to Baker Perkins Limited, Peterborough, EnglandApplication September 11, 1942, Serial No. 458,044
In Great Britain September 24, 1941

6 Claims. (Cl. 107—7)

This invention relates to apparatus for feeding biscuits or other sweetmeats (hereinafter referred to as "biscuits") from an oven or other source of supply to a chocolate enrobing or coating machine or the like or for delivery of articles to other machinery or for collection.

An object of the invention is to provide an apparatus adapted to receive biscuits from an oven or other source from which they are discharged in a continuous train (of substantially equally spaced rows or of indiscriminately spaced biscuits) and deliver such in batches, that is to say in groups separated from one another by intervals which suitably divide the train into batches, to chocolate enrobing or coating machines and the like (hereinafter referred to as "enrobers") so that the batches of biscuits may be transferred from the enrober to separate plaques for cooling purposes, an aim of the invention being to provide a simple apparatus adapted to handle the biscuits without disturbing their relative position in the batches. A further aim of the invention is to provide an apparatus of the above character in which vibration and noise are reduced to a minimum, reciprocation of parts is eliminated and the difficulties attendant upon the employment of a series of co-operating endless bands for batching the biscuits in transfer from one band to another are overcome.

The invention consists in apparatus having a series of biscuit batching aprons propelled at two different rates, the slower rate being employed while an apron is receiving biscuits while the faster rate is employed to separate a filled apron from the following apron to form a batch space and while the biscuits are being discharged.

The invention also consists in apparatus having a pair of tracking chain means travelling at different rates and adapted to drive a series of biscuit batching aprons over a table from a feeding position to a discharging position, the arrangement being such that a filled apron is accelerated to space it from an apron being filled, while being discharged, and in returning it to the feed position to cause its head to be overlapped by the tail of the apron which precedes it at the slower rate in travelling to the feed end of the table and while being filled with biscuits.

In the accompanying drawings—

Figures 1 and 1a together show in side elevation a batching apparatus according to the invention.

Figure 2 is an end elevation, and

Figures 3 and 3a together show a partial plan corresponding to Figures 1 and 1a.

In carrying the invention into effect according to one convenient mode as described by way of example, a horizontal table 1 is provided over which a series of biscuit-carrying aprons or plaques 2a, 2b, 2c, etc., are adapted to travel. The table may be of smooth metal or spaced bars 1 (see Figure 2) and is of a length appropriately longer than a single apron so that whilst one apron 2a is on the table another 2b is beginning 5 to receive biscuits whilst a third 2c is discharging or finishing its discharge of biscuits already batched. Both ends of the table may be curved downwardly to facilitate the travel of the aprons around the ends of the table.

10 The aprons 2a, 2b, 2c each comprise a piece of canvas or other suitable flexible material somewhat longer than the length from front to rear of the batch it is intended to receive. The width of the apron is slightly greater than the width of the train of biscuits. The head of the apron is attached to a flat or other appropriately shaped driving bar 3 which projects laterally beyond the sides of the apron so that the projecting ends may be engaged by propelling lugs (which may 15 be of angular form) carried by chain traction means. The aprons are pulled up on to the table around the curved feed end F and are traversed along the table to the delivery end D, where they are pulled downwardly over the curved delivery 20 portion of the table and are carried back to the feed end of the machine along a track comprised of spaced longitudinal bars 4. These bars terminate at a point spaced from the feed end and are succeeded by a pair of bars 5 which support the 25 apron bars 3 but allow the apron to trail freely so as to ensure the leading apron to lie outside or above the following apron as hereinafter described.

The means for propelling the aprons 2a, 2b, 2c 30 comprise two pairs of traction chains 6, 7 travelling at different speeds and carrying a series of propelling lugs 8, 9 for engaging the driving bars 3 of the aprons. One pair of chains 6 (slow moving) has its upper lap extending parallel with 35 and below the table 1. At the feed end turning point F chain wheels 10 are provided and another pair of chain wheels 11 is provided towards but not at the delivery turning point. The chain wheels 10 and 11 are mounted so that their axes 40 lie transversely of the table and position the chains 6 one on each side of the table 1 so that the propelling lugs 8 of the chains 6 may engage the driving bars 3 of the aprons. The chains 6 travel parallel with the table through their upper 45 lap and on their return lap pass around guide 50 bars 5. The propelling lugs 8 are provided with 55 projections to engage the driving bars 3.

sprockets 12 and 13. The chain wheels 10 at the feed end and the guide sprockets 13 are adjustably mounted for the purpose of adjusting the position of the lugs 8 relatively to the lugs 9 of the chains 1. The slow moving chains 6 are adapted to travel at a rate corresponding with the rate of the travel of the oven or endless band supplying the biscuits to the feed end of the table and at a slower rate than the rate of travel of the enrober wire.

The second (faster moving) pair of chains 7 passes around the chain wheels 14 at the delivery turning point D of the table and around guide chain wheels 15 and 16 below the table. From the guide return chain wheels 16 the chains 7 travel on an upward slope to guide chain wheels 18 which are disposed to the rear of the terminal chain wheel 11 of the chains 6 so that the chains 7 have a short portion of the upper lap coinciding with the chains 6 to provide a change over point where the faster chain lugs 9 engage the bars 3 of the aprons and carry them forwardly away from the slower chain lugs 8 so that the aprons are propelled at the accelerated rate. The actual change over occurs adjacent the chain wheels 18. The faster moving chains 7 travel at the same rate as the enrober wire, the proportionate rates of the faster and slower moving chains being such that when the faster moving lugs 9 pick up an apron bar 3 from the slower moving lugs 8 the rate of advance of the apron is increased to such an extent that the last row of biscuits thereon is spaced from the foremost row of the next following apron by a distance which may be predetermined as appropriate for the batch interval.

The axes of the guide wheels 16 are coincident with the axes of the guide wheel 12 of the chains 6. At this point a second change over occurs where the faster moving lugs 9 leave the apron bars 3 (on the return journey) which are then caught up by the slower moving lugs 8.

After discharge the aprons pass downwardly beneath the lower guide wheels 15 and then upwardly along an incline to the feeding end of the table. The apron supporting bars 4 are bent to conform to the downward and upward inclined tracks.

The proportions of the track and length of apron are such that as the head of an apron reaches the change over guide wheels 12 and 16 the tail of the preceding apron falls down between the pair of bars 5 with a view to ensuring that the head of the apron as it reaches the turning point at the feed end of the table will be overlapped by the tail of the apron in front. The aprons are propelled by the lugs 8 of the slower chain 6 for the greater part of their travel over the table and when the head of an apron is approaching the delivery end and the tail end has passed the loading point the lugs 9 of the faster chains 7 catch up the driving bars 3 and take them from the lugs of the slower chains.

When the faster moving lugs 9 take charge of a traction bar 3 its apron is accelerated to the speed of the enrober wire and the biscuits are discharged as the apron is bent downwardly over the rounded delivery end D of the table and propelled by the faster moving chains 7 on its downward return path until the pusher bar arrives at the change over wheels 12 and 16 where the faster pusher lugs 9 move upwardly around the wheels 16 leaving the bar 3 to be engaged by the lugs 8 of the slower moving chain as they move downwardly around the wheels 12. The slower moving

lugs 8 propel the apron by its traction bar 3 upwardly towards the feeding end and around the curved end F of the table. The forward portion of the apron will merge on to the table with the tail of the preceding apron overlapping it. The aprons thus present a continuous receiving surface travelling at a speed uniform with the feeding band, so that the biscuits transferred are not disturbed in spacing during this operation. When

10 an apron comes under the control of the lugs 9 of the fast moving chains the load carried on it is moved away bodily from that on the succeeding apron without disturbance of the relative position of the biscuits comprising the batch, and the interval between the batches is determined by the extra distance travelled during the passage of the apron at the faster speed over the length allowed.

At the feed and delivery end guides 25 and 26 are provided for guiding the bars of the aprons.

20 The drive to the chains 6 and 7 is taken from a drive shaft 17 on to a lay shaft 25, through bevel pinions 19, 20 to a shaft 21. The shaft 21 is provided with the chain wheels 15 for driving the fast moving chains 7. The shaft 21 drives an upper shaft 22 by chain and sprockets 23, 24, such upper shaft carrying the chain wheels 11 by which the slower moving chains 6 are driven.

25 The aprons may discharge direct to the enrober or may deliver on to a short endless conveyor band or wire which passes over a knife edge positioned closely adjacent the delivery end of the table. The gap between the table and the band at the knife edge need not be wider than to afford a suitable clearance for the passage of the delivering apron. The other end of the conveyor band discharges directly on to the enrober wire.

30 At the feed end an endless band feeds a continuous train of biscuits from an oven band or other continuous source of supply. The band at 40 the feed end of the table passes over a knife edge which, like that of the delivery receiving band, is spaced from the table a distance sufficient to afford a suitable clearance for the passage of the aprons in being drawn on to the table or the band may overlap the plaques.

35 Where necessary, guide plates or guards may be provided to maintain the aprons in their required track in passing from the delivery to the feed end of the table and below the delivery end 50 a shoe may be mounted to press upon the side edges of the apron so as to maintain the apron under suitable tension.

45 While the invention has been described in more particular reference to an enrober, it may be applied in other surroundings for splitting up an endless train into batches for delivering such to conveyors or machinery adapted to deal with the goods in the batch form, or for delivering the batches to trays for collection, stacking or packing.

55 I claim:

1. Apparatus for feeding biscuits from an oven or other source of supply to a coating machine comprising a series of batching aprons mounted 65 to travel through a closed circuit, said aprons adapted to receive biscuits from the supply and deliver them to the coating machine, means for driving the aprons at one rate whilst receiving biscuits, and means for driving the aprons at a higher rate to separate a filled apron from the following apron and while being discharged.

2. Apparatus for feeding biscuits from an oven or other source of supply to a coating machine comprising a series of batching aprons mounted 70 to travel through a closed circuit, means for sup-

porting the aprons between a feeding position and a discharge position, endless traction means, means for driving said traction means at one speed, a second endless traction means, means for driving said second traction means at a higher speed, means for driving the aprons by the slower moving traction means while receiving biscuits and means for driving the aprons by the faster moving traction means to separate the aprons and while discharging biscuits.

3. Apparatus for feeding biscuits from an oven or other source of supply to a coating machine comprising a series of batching aprons mounted to travel through a closed circuit, means for supporting the aprons between a feeding position and a discharge position, driving bars at the leading ends of the aprons, a pair of endless traction chains travelling in a path including the feeding position, means for driving said chains at one speed, lugs on the chains adapted to engage said bars for driving the aprons, a second pair of endless traction chains travelling in a path including the discharge position, means for driving said second pair of chains at a speed higher than that of the first pair of chains, lugs on the second pair of chains adapted to engage said bars for driving the aprons at the higher speed, the paths of the pairs of chains overlapping at a position where the lugs on said faster moving chains remove the bars from the control of the

30 lugs of the slower moving chains, and at a second position where the lugs of the faster moving chains release the bars whereby the bars are engaged by the lugs on the slower moving chains.

5. Apparatus as claimed in claim 3, wherein the slower moving chains pass over adjustable guide sprocket wheels, whereby the slower moving lugs may be timed relatively to the faster moving lugs.
- 10 5. Apparatus as claimed in claim 3, wherein apron supporting spaced bars are provided between the discharge position and the position where the faster moving lugs leave the apron driving bars, the aprons hanging freely between 15 such position and the feed position to ensure the trailing end of one apron overlapping the leading end of the succeeding apron during the feeding of biscuits thereto.

6. Apparatus for receiving articles from a continuous column and delivering them in batches, comprising a series of batching aprons mounted to travel through a closed circuit past an article receiving station, means for driving the aprons at one rate whilst receiving articles from said column, and means for driving the aprons at a higher rate to separate a filled apron from the following apron and while discharging a batch of articles.

ALLAN ASHMEAD TUNLEY.
